UNITED STATES PATENT OFFICE.

ELI JONES, OF LUVERNE, MINNESOTA.

THREAD CUTTING AND TAPPING MACHINE.

1,392,170.

Specification of Letters Patent. Patented Sept. 27, 1921.

Application filed March 11, 1920. Serial No. 364,998.

To all whom it may concern:

Be it known that I, ELI JONES, a citizen of the United States, and a resident of Luverne, in the county of Rock and State 5 of Minnesota, have invented a new and Improved Thread Cutting and Tapping Machine, of which the following is a full, clear, and exact description.

This invention relates to improvements 10 in thread cutting and tapping machines, an object of the invention being to provide improved means for supporting and mounting a longitudinally movable chuck and provide improved means for turning the 15 chuck in either direction.

A further object is to provide improved means for clamping the work either in a horizontal or vertical position.

A further object is to provide a machine 20 of the character stated which will be of extremely simple construction, strong and durable in use, and which most efficiently performs the functions for which it is intended.

With these and other objects in view the invention consists in certain novel features 25 of construction, and combinations and arrangements of parts, as will be more fully hereinafter described and pointed out in the 30 claims.

In the accompanying drawings—

Figure 1 is a plan view illustrating my improved machine;

Fig. 2 is a view in side elevation;

Fig. 3 is a view in longitudinal vertical 35 section;

Fig. 4 is a view in section on the line 4—4 of Fig. 3; and

Fig. 5 is a view illustrating a tap which 40 may be employed with my improved chuck.

1 represents a support and 2 a metal base secured on the support and provided with aligned bearing brackets 4 and 5 and with a bearing bracket 6 at right angles to the 45 brackets 4 and 5 and located on a median line therebetween. The bracket 6 supports a drive shaft 7 and the brackets 4 and 5 support a driven shaft 8. A beveled pinion 9 is fixed to the drive shaft 7 and a drive 50 pulley 10 is also fixed to the shaft 7 and driven by a belt 11 from any suitable source of power.

Facing beveled gears 12 and 13 are mounted 55 loosely on the shaft 8 and a sliding clutch 14 is located on the shaft 8 between the gears

12 and 13 and is adapted to be moved by means of a lever 15 so as to lock either of said gears to the shaft 8 or to lie at an intermediate position between them. The lever 15 is horizontally mounted and is angular 60 in form and is pivotally connected, as shown at 16, to a post 17 on the base 2. The long end of the lever 15 extends longitudinally of the machine and rests upon a laterally projecting arm 18 carried by bracket 5. 65

On the free end of the driven shaft 8 my improved chuck 19 is located and is provided with a relatively long sleeve 20 keyed to slide on the shaft 8, any desired number of keyways or grooves 21 being provided in the shaft 8. The chuck 19 is moved longitudinally on the shaft 8 by means of a lever 22, the latter having a slotted portion 23 pivotally connected at its sides to trunnions 24 on a collar 25. The collar 25 is loose on the sleeve 20 of the chuck and is mounted between fixed collars 26 and 27. The lower end of the lever 22 is provided with a lug 28 which is located in an opening 29 in an arm 30 projecting from the bracket 5 so 70 that the swinging movement of the lever operates to move the chuck longitudinally.

On the base 2 at one end angle brackets 31 and 32 are secured and located parallel to each other. A transversely positioned 75 rod 33 is projected through the brackets 31 and 32 and transversely movable vise members 34 and 35 are movable on the rod 33 and are operated by means of a screw threaded rod 36 which extends through the members 34 and 35 and through the brackets 31 and 32 and is provided with right and left hand screw threads engaging the respective members so that when the rod 36 is turned, the members 34 and 35 will be moved toward or away from each other. A crank arm 37 provided at one end of the rod 36 facilitates its adjustment. These members 34 and 35 have clamping 80 jaws 38 to engage the work and support it 95 in a horizontal position.

To support the work in a vertical position, a third vise member 39 is located in parallelism with the member 34 and at its lower end is slidable upon a bolt 40 secured to the member 34 and projecting through the member 39 and having a nut 41 thereon limiting the movement of the member 39. A coiled spring 42 is positioned around the bolt 40 between the members 34 and 39 and 100 110

- tends to press the member 39 away from the member 34. A screw threaded rod 43 is mounted in the member 34 and has screw threaded engagement with the member 39 so that when this rod 43 is turned, it will serve to move the member 39 toward or away from the member 34. A crank arm 44 is provided on the rod 43 to turn the same.
- 10 The chuck 19 is provided with a set screw 46 which is adapted to clamp a die 47 in the chuck, or a tap 48, as indicated in Fig. 5, may be substituted for the die in accordance with the work to be done. This invention is, of course, not limited to the particular form of die or tap employed as I may use any standard die and tap in accordance with the work to be done.
- 15 In operation, the work is clamped at the end of the base 2 by the members 34 and 35 or by the members 34 and 39 and the chuck 19 is moved toward the work by means of the lever 22. The clutch 14 is operated to lock either of the gears 12 or 13 to the driven shaft 8 in accordance with the direction of movement desired, and the desired length of thread can be cut or the desired length of tap can be made by adjusting the work in the clamping members 20 and by moving the chuck. After the work is finished, the lever 15 is operated to move the clutch 14 to an intermediate position so as to permit the gears 12 and 13 to turn idly on the shaft 8 and allow a free manipulation of the dies and taps in the chuck in accordance with the work to be done.
- 25 Various slight changes may be made in the general form and arrangement of parts described without departing from the invention, and hence I do not limit myself to the precise details set forth but consider myself at liberty to make such changes and alterations as fairly fall within the spirit and scope of the appended claims.

I claim:

45 1. A machine of the character described, comprising a drive shaft, a driven shaft at right angles thereto, facing beveled gears loose on the driven shaft, a pinion fixed to the drive shaft and meshing with both of said gears, a clutch adapted to secure either of the gears to the driven shaft and normally spaced from both of said gears, a chuck keyed to slide on the driven shaft, a support, and a chuck moving lever fulcrumed at one end in said support and operatively connected at a point removed from its fulcrum with said chuck.

50 2. A machine of the character described, comprising a drive shaft, a pinion on the drive shaft, a driven shaft, gears loose on the driven shaft and meshing with the pinion, a clutch on the driven shaft normally spaced from the gears and movable into locked engagement with either of the gears, a chuck keyed to slide on the driven shaft, a slotted lever straddling the chuck, a lug on the end of the lever, a slotted arm receiving the lug, and means operatively connecting the slotted portion of the lever 55 with the chuck.

55 3. A machine of the character stated, comprising a support, a horizontal shaft on the support, means for turning the shaft in either direction, a chuck on the shaft, a 60 pair of brackets on the shaft, a transversely positioned rod connecting the brackets, a pair of transversely movable vise members mounted on the rod, a second rod having right and left hand screw threads engaging the respective vise members, a third vise member movable longitudinally of the support, a spring exerting pressure on the last-mentioned vise member tending to move it in one direction, and a screw engaging the 65 last-mentioned vise member adapted to move it in the opposite direction.

70 80 85 ELI JONES.
